CLAIM

The ornamental design for a bottle lid, as shown and described.

DESCRIPTION

FIG. 1 is a perspective view of a bottle lid embodying the claimed design, shown in a position of use attached to a bottle drawn in broken line.

FIG. 2 is a bottom perspective view of the bottle lid.

FIG. 3 is a top plan view of the bottle lid.

FIG. 4 is a front elevation view of the bottle lid.

FIG. 5 is a left-side elevation view of the bottle lid, with the right-side elevation view being a mirror image thereof.

FIG. 6 is a rear elevation view of the bottle lid.

FIG. 7 is a bottom plan view of the bottle lid; and,

FIG. 8 is an exploded perspective view showing the bottle lid, disassembled to reveal the compartment for containing items therein.

The dash-dash broken lines in FIG. 1 showing a bottle depict environmental structure and form no part of the claimed design. The dash-dot-dash broken line in FIG. 8 leading from the top of the bottle lid to the bottom of the bottle lid indicates the direction of assembly of the design and forms no part of the claimed design. All other broken lines depict portions of the bottle lid that form no part of the claimed design.
